FAN

Edmund E. Hans, Detroit, Mich.

Application June 18, 1941, Serial No. 398,510

2 Claims. (Cl. 230—120)

This invention relates to improvements in fans. The invention aims, among other things, to provide a fan primarily intended for use in automobile heaters and air conditioning systems, which can be driven by quite a small motor, say an electric motor drawing about fifty watts, and which will deliver a relatively large volume of air, say about four hundred feet, at a relatively high pressure, say about one-half to one inch of water.

Another object of the invention is to provide a fan having a relatively large number of transversely inclined blades which overlap one another throughout their entire radial length, and which are mounted in an orifice of only very slightly larger diameter than the distance between the peripheries of radially opposed pairs of blades, so that the blades rotate partly in the orifice and partly within a casing of larger cross section than the orifice extending from the discharge side of the latter.

A further object of the invention is to provide such a fan wherein an inwardly projecting annular flange is provided around the inlet side of the orifice to prevent backflow of air through the latter.

Yet another object of the invention is to provide a fan wherein the hub consists of two discs superimposed one upon the other each having an equal number of transversely inclined blades projecting therefrom, and the trailing edges of the blades projecting from the upper disc slotted adjacent the latter to coact with corresponding slots formed in the leading edges of the blades projecting from the lower disc so that the trailing edges of the blades on the upper disc may extend beneath and overlap the leading edges of the blades on the lower disc.

Another object of the invention is to provide such a fan which is relatively cheap and simple to manufacture and highly efficient in operation.

Having thus briefly stated some of the objects and advantages of the invention I will now describe one embodiment thereof with the aid of the accompanying drawings, in which:

Figure 1 illustrates a side view thereof, and the casing in section, and

Figure 2 is an inverted plan view.

Figure 3 is a plan view of the upper plate and the blades thereon.

Figure 4 is a somewhat enlarged sectional view of the bushing and the plates mounted thereon.

Figure 5 is a sectional view on the line 5—5 of Figure 3 showing a cross section of one blade on the upper plate, and

Figure 6 shows a similar cross section on the lower plate.

Referring to the drawings, 1 designates a supporting member having a circular orifice 2 formed therethrough around the inlet side of which an annular inwardly projecting flange 3 is provided. The supporting member 1 is mounted in a suitable casing 1a of larger cross section than the orifice 2, and formed integral with the 10 said member is a spider 4 terminating in a split ring 5 in which a motor 6 is supported concentrically with the said orifice. The split ring 5 is secured around the motor 6 by a screw 7 by which the adjacent extremities of the split ring are drawn together. Suitably secured around the shaft 8 of the motor 6 is a bushing 9.

10 and 10a denote two plates superimposed one upon the other. Each plate 10 and 10a has a centrally apertured disc 11 and 11a from which uniformly spaced and transversely inclined radial blades 12 and 12a extend. The two discs 11 and 11a, which together form a hub, are secured upon the bushing 9 and held immovable thereon as by riveting over the outer circumference of the latter at one extremity as shown at 9a.

Formed in the trailing edges of the blades 12 adjacent the disc 11 are slots 14, and formed in the leading edges of the blades 12a adjacent the disc 11a are corresponding slots 14a. The 20 two plates 10 and 10a are relatively so mounted upon the bushing 9 that each blade 12 on the upper plate 10 is equidistant between two adjacent blades 12a on the lower plate 10a, and the width of all the blades is such that each 25 projects circularly beyond the adjacent margins of the blade on each side of it. The provision of the cooperating slots 14 and 14a permits the overlapping of the downturned trailing edges of the upper blades 12 so that they 30 may extend beneath the leading edges of the blades 12a on the lower plate 10a.

The formation of the blades is clearly shown in Figures 5 and 6 from which it will be seen that the trailing edges 12' of the blades 12 on the upper disc 11 project farther downward from the latter than the trailing edges 12a' below the disc 11a, and the leading edges 12'' of the said blades 12 on the upper disc 11 do not project so far upward as the leading edges 12a'' of the blades 12a on the lower disc 11a. Consequently when the two plates 10 and 10a are mounted in position the leading edges of all the blades 12 and 12a, and also all their trailing edges, are in alignment.

55 Due to the fact that the opening through

the annular flange 3 is less than the distance between the peripheries of opposed pairs of blades 12 and 12a, and the bore of the orifice 2 is only very slightly greater than the aforesaid distance, backflow of air through the orifice is practically completely eliminated. And further since the blades lie partly in the orifice 2 and extend partly below the latter into the casing 1a which is larger in cross section than the orifice a relatively free discharge from the fan is obtained so that the efficiency is further increased. Due also to the continuous circular overlap of the blades air slippage is very largely eliminated and greater efficiency obtained, particularly where it is desired to discharge air at some pressure through a somewhat restricted area such as the casing 1a.

As the size of the blades on both plates 10 and 10a is the same both plates may be blanked out, including the formation of the slots 14 and 14a, by the same dies. To form the blades in the upper plates 10 the blanks are placed in the forming die with their slots trailing, and to form the blades for the lower plates 10a the blanks are placed in the same forming die with their slots leading (by turning the plates over). Moreover when forming the upper plates 10 a spacing piece must be inserted in the die beneath the disc portion 11 to raise the latter so that the variation referred to in the upward and downward projections of the blades is produced. Thus the same blanking and forming dies may be employed to manufacture both the upper and the lower plates.

I claim:

1. In a fan, the combination of two plates

each having a central disc and a plurality of blades provided with radially extending edges, said blades having decreasing transverse pitch and increasing width toward their outer ends, 5 and having the outer margins thereof concentric to the axis of the discs, said discs being superimposed one upon another so that the radial edges of the blades are slightly overlapped, and the combined peripheries of the blades form a 10 cylinder, a ring surrounding the periphery of the blades and having an inturned flange thereon forming a corner between the ring and flange, said fan being mounted in said ring so that the blade ends occupy said corner.

15 2. A fan comprising a support, a ring having an orifice therein carried by the support, a fan element having blades mounted in said ring with the blades lying partially within said orifice and projecting outwardly from one side of the ring, 20 said orifice being only slightly larger than the diameter of the blades, said fan comprising two plates each having a central disc and a plurality of blades provided with radially extending edges, said blades having decreasing transverse pitch and increasing width toward their outer ends, and having the outer margins thereof concentric to the axis of the discs, said discs being superimposed one upon another so that the radial edges of the blades are slightly overlapped 30 and the combined peripheries of the blades form a cylinder, an inturned flange on said ring forming a corner at the junction of the ring and flange, said fan blades occupying said corner.
